UNITED STATES PATENT OFFICE.

ZOTIQUE BEAUDRY, OF LYNN, MASSACHUSETTS.

JACK FOR BOOTS OR SHOES.

SPECIFICATION forming part of Letters Patent No. 764,335, dated July 5, 1904.

Application filed November 27, 1903. Serial No. 182,758. (No model.)

To all whom it may concern:

Be it known that I, ZOTIQUE BEAUDRY, a citizen of the United States, residing at Lynn, in the county of Essex and State of Massachusetts, have invented new and useful Improvements in Jacks for Boots or Shoes, of which the following is a specification.

This invention relates to an improved jack for holding boots and shoes, the same being particularly adapted for use in connection with machines for trimming, burnishing, or setting the edges of the soles and heels of said boots and shoes.

The object of the invention is to provide a jack which can be readily adjusted to hold boots and shoes firmly in position to be operated upon, the device being so constructed that the shoe can be held with either the toe or the heel uppermost and adapted to hold said shoe so that it may be rotated or rocked into different positions.

The invention consists in the combination and arrangement of parts set forth in the following specification and particularly pointed out in the claims thereof.

Referring to the drawings, Figure 1 is a side elevation of my improved jack with a shoe clamped thereto with the toe pointing upwardly, the same being illustrated fastened to a portion of a supporting-frame, said supporting-frame being broken away to save space in the drawings. Fig. 2 is an enlarged section taken on line 2 2 of Fig. 1. Fig. 3 is a side elevation of a portion of the jack with the shoe-holder and the collar and arm to which it is connected shown separated. Fig. 4 is a side elevation of a portion of the jack with a shoe clamped thereto, the heel being uppermost. Fig. 5 is an enlarged section taken on line 5 5 of Fig. 1.

Like numerals refer to like parts throughout the several views of the drawings.

In the drawings, 10 is a U-shaped jack-frame fast to and supported upon a frame 11 of any suitable construction. The vertical arm 12 of the jack-frame has a shoe-support 13 rotatably mounted thereon, said shoe-support being provided with a cylindrical shank 14, constructed to rotate in the upper end of the arm 12 and prevented from moving longitudi-

nally therein by a screw 15, the inner end of which projects into a groove 16, provided in the shank 14. A rotatory clamp-slide 17, cylindrical in cross-section, is mounted to slide in ways 18, provided in the upper end of the vertical arm 19 of the jack. A collar 20 is fast to the slide 17 between the arms 12 and 19 of the jack and is guarded from longitudinal motion upon said slide by a screw 21, the inner end of which bears against the slide 17.

In Figs. 1, 2, and 3 a fore-part holder 23 is mounted upon the slide 17 and is detachably connected to the collar 20 by a spring-plate 24, the left-hand end of which is supported upon the screw 21 and held against the collar 20 by a spiral spring 25, which encircles said screw 21 and bears at one end against the plate 24 and at the other end against a washer 26, located beneath the head of said screw. A pin 27, fast to the fore-part shoe-holder 23, projects through a slot 28, provided in the plate 24. The fore-part holder 23 is bored out to receive the cylindrical slide 17 and beyond the right-hand end of said slide to receive a spiral spring 29, one end of said spiral spring 29 bearing against the end of the slide 17, the other against the bottom of the recess 30 in the shoe-holder 23. The holder 23 is provided with a downwardly-extending arm 31, to the lower end of which is pivoted at 32 a lever constituting a heel-holder 33. The right-hand end of the heel-holder 33 is curved to fit and partially encircle the heel of a shoe 34, clamped to the support 13 by the fore-part holder 23, as hereinafter described. The opposite end of the heel-holder 33, at the left of the pivot 32, is provided with a segment 35, having a corrugated surface 36, which engages another corrugated surface 37, formed upon an arm 38 integral with and projecting downwardly from the collar 20. The segment 35 plays between two flanges 39 39 integral with the arm 38. A pin 40 limits the extent to which the heel-holder 33 may be tipped upon its pivot by abutting against the arm 31.

A reciprocating motion is imparted to the slide 17 by a bell-crank lever 41, pivoted at 42 to the jack-frame 10. The vertical arm of the bell-crank lever 41 engages a forked bracket 100

43, rotatably mounted upon the slide 17, said bell-crank lever projecting between the arms of said forked bracket and being rounded on its opposite edges to engage on the right 5 thereof said bracket and on the left a friction-roll 44, journaled to rotate upon said bracket. The bracket 43 is fastened to the slide 17, in such a manner that said slide is free to rock in said bracket, by a set-screw 48, which projects at its inner end into a groove 22, formed in the periphery of the slide 17. The pressure of forcing the slide 17 toward the right in order to clamp a shoe to the shoe-holder is taken by a shoulder formed upon the slide 17 10 and bearing against the right-hand side of the forked bracket 43. The screw 48 keeps the bracket 43 and slide 17 together when the slide 17 is being withdrawn from the shoe or moved toward the left. The horizontal arm 15 of said bell-crank lever is pivotally connected to a treadle-rod 45, which extends downwardly and is connected to a suitable treadle. (Not shown in the drawings.) Said rod is depressed by the treadle and raised by a spiral 20 spring 46, fast at one end to said rod 45 and at the other to the jack-frame 10.

When the shoe is removed from the machine, the fore-part holder 23, heel-holder 33, and collar 20, together with the depending 25 arms 38 and 31, assume the positions relatively to the jack-frame illustrated in Fig. 3, said collar and shoe-holder being forced apart by the action of the spiral spring 29, and thus disengaging the corrugated surfaces 36 30 and 37, allowing the heel-holder to drop into the position shown, with the pin 40 resting against the arm 31. In placing the shoe in position for the edges of the sole to be operated upon, said shoe is placed in the machine 35 in the position indicated in Fig. 1, with the toe uppermost and the fore-part holder bearing against the upper of the shoe midway between the toe and shank thereof. The heel-holder is free to be rocked upon its pivot, as 40 shown in Fig. 3, and is tipped upwardly until the right-hand end thereof firmly engages the heel of the shoe 34. The operator now places his foot upon the treadle and depresses the treadle-rod 45, rocking the bell-crank lever 45 upon its pivot and moving the slide 17, together with the collar 20 and its depending arm 38, toward the right, Fig. 1, until the corrugated surfaces 36 and 37 engage one with the other, and thus lock the heel-holder 50 firmly in position, while the shoe-holder 23 is brought to bear against the toe portion of the shoe. The shoe is now in position to have the edges of the sole trimmed or burnished, as the case may be, it being understood 55 that the shoe-holder 23, heel-holder 33, arms 31 and 38, collar 20, and slide 17 are free to be rocked backward and forward, said slide 17 rocking in the bearing 18 and forked bracket 43 and the shoe-support 13 rocking 60 with them. When it is desired to operate 65

upon the edges of the heel of the shoe 34, the shoe-holder 23 is removed by springing the plate 24 outwardly until it disengages the pin 27 and slipping said holder off of the slide 17. A holder 47, Fig. 4, is then placed upon the 70 slide 17 and is held thereon by the plate 24 and pin 27, the end of said holder 47 bearing against the inside of the heel of the shoe. Said shoe is clamped to the support 13 by means of the slide 17, as hereinbefore described. 75

It is evident that instead of the corrugated surface 37 a single tooth might be used without departing from the spirit of my invention, said tooth being constructed to engage 80 the corrugated surface 36.

Having thus described my invention, what I claim, and desire by Letters Patent to secure, is—

1. A jack for boots and shoes comprising 85 in its construction a frame, a reciprocatory clamp-slide constructed to slide thereon, a collar and a shoe-holder, both mounted on said slide, and means to detachably connect said collar and holder together. 90

2. A jack for boots and shoes comprising in its construction a frame, a reciprocatory clamp-slide constructed to slide thereon, a collar and a shoe-holder, both mounted on said slide, a spring-plate supported upon said collar, and a pin fast to said holder and projecting into a slot provided in said spring-plate. 95

3. A jack for boots and shoes comprising in its construction a frame, a reciprocatory clamp-rod constructed to slide thereon, a collar and a fore-part shoe-holder, both mounted on said rod, a heel-holder pivoted to said fore-part holder, and means to lock said heel-holder to said collar. 100

4. A jack for boots and shoes comprising 105 in its construction a frame, a reciprocatory clamp-rod constructed to slide thereon, a collar, an arm provided with a corrugated surface fast to said collar, a fore-part shoe-holder, said collar and holder mounted on said rod, a 110 heel-holder, consisting of a lever pivoted to said fore-part holder, one end of said lever constructed to engage the heel portion of a shoe, the opposite end thereof corrugated to engage the corrugated surface upon said arm. 115

5. A jack for boots and shoes comprising in its construction a frame, a reciprocatory clamp-rod constructed to slide thereon, a collar and a fore-part shoe-holder, both mounted on said rod, a heel-holder supported upon said 120 fore-part holder, and adapted to be adjusted to support shoes of different sizes.

6. A jack for boots and shoes comprising in its construction a frame, a reciprocatory clamp-rod constructed to slide thereon, a collar, an arm provided with a corrugated surface fast to said collar, a fore-part shoe-holder, said collar and holder mounted on said rod, a 125 heel-holder, consisting of a lever pivoted to said fore-part holder, one end of said lever 130

constructed to engage the heel portion of a shoe, the opposite end thereof corrugated to engage the corrugated surface upon said arm, and a spring acting to move said collar and holder apart.

7. A jack for boots and shoes comprising in its construction a frame, a shoe-support rotatably mounted thereon, a reciprocatory clamp-rod constructed to slide upon said frame, a collar and a shoe-holder both mounted on said rod, and means to detachably connect said collar and holder together.

8. A jack for boots and shoes comprising in its construction a frame, a reciprocatory clamp-rod constructed to slide thereon, a collar, an arm provided with a corrugated sur-

face fast to said collar, a fore-part shoe-holder, said collar and holder mounted on said rod, a heel-holder consisting of a lever pivoted to said fore-part holder, one end of said lever constructed to engage the heel portion of a shoe, the opposite end thereof corrugated to engage the corrugated surface upon said arm, and flanges upon said arm, between which said lever projects.

In testimony whereof I have hereunto set my hand in presence of two subscribing witnesses.

ZOTIQUE BEAUDRY.
